LOOSE LEAF BINDER

Erik L. Krag, Chicago, Ill., assignor of one-tenth
to E. J. Andrews, Chicago, Ill.

Application May 29, 1933, Serial No. 673,379

2 Claims. (Cl. 129—1)

This invention relates to loose-leaf binders, and has for its object providing various improvements in the ordinary binders in use, particularly with reference to the means for removing and inserting leaves, and for shifting them from one position on the binder to another.

Of the accompanying drawings, Fig. 1 is a fractional plan view of a binder which embodies some of the features of my invention; Fig. 2 is a front end view of the binder; Figs. 3, 4 and 5 are transverse sectional views of the binder along the respective lines 3—3, 4—4 and 5—5 of Fig. 1; Fig. 6 is a fractional plan view of a modified form of binder; Fig. 7 is a fractional side view of the same; Fig. 8 is a plan view of a further modification; and Figs. 9 and 10 are sectional views along the respective lines 9—9 and 10—10 of Fig. 8.

It is customary with loose-leaf binders to provide means for shifting the sets of paper holding prongs towards and away from each other transversely of the binder. In such cases, the prong holding means are also shifted bodily with the prongs. In this case, however, I prefer to tilt or rotate the sets of prongs away from each other when the leaves are to be changed. One or both sets may be made tilttable, as may be desired. In Figs. 1 to 5, I show the left set only tilttable. By using upwardly projecting and inwardly arched prongs, with their lower ends fixed to a rotatable holding strip, the upper ends may be tilted outwardly sufficient to allow the leaves to be shifted as desired.

For this purpose, I provide a base plate 10 extending the full length of the binder. Preferably, on the right-hand edge, a support strip 11 is fixed for holding the immovable set of prongs 12. On the other edge of the plate, I provide a strip 13 for the other set of prongs 14. This strip 13 is rotatably mounted, preferably on a rod 15, so that the upper ends of the prongs may be tilted away from the prongs 12, as in Fig. 4. Whenever it is desired to insert or remove leaves from either set of prongs, it is necessary only to tilt or rotate the prongs 14 outwardly and proceed in the ordinary manner.

To prevent inadvertent opening of the prongs, I provide means for locking them in their closed positions. Preferably these means comprise a strip 16 non-rotatably associated with the prong strip 13, and having an inwardly projecting flange 17. Pivotedly mounted on the plate 10 is an arm 18 adapted to be rotated so that the free end will project outwardly over the flange 17, holding it in the closed position. To operate the arm 18, I provide a longitudinal bar 19 slidably mounted

on the plate 10 and with one end extending to the front end of the binder. A handle 20 is provided for operating this bar. The arm 18 is also pivoted to the bar 19, by means of a slot 21, and by operating the bar the free end of the arm 5 may be passed onto or off from the flange 17.

As many locking means 18 as may be desired may be applied, operating simultaneously by means of the bar 19. And suitable guide means and stop means may be provided for the bar. Also 10 these various means may be provided for binders which merely open the prongs or for those which also provide for shifting the sets of prongs longitudinally with reference to each other.

In this instance, I provide for shifting bodily 15 the tilttable set of prongs longitudinally of the binder. These means comprise the strip 13 and the rod 15. The strip is both rotatably and slidably mounted on the rod by means of a strip 22. The strips 13, 16 and 22 are rigidly connected in any suitable manner, such as by means 20 of rivets 23. A handle 24 is formed on the front end of these strips for operating the prongs either tiltably or longitudinally.

I also provide means for registering the movable prongs with reference to the others. In this case, these means comprise a strip 25 having notches 26 in one corner. A flange 27 projects downwardly from the handle 24 and passes into one of the notches as the prongs are closed in the 30 proper relative positions. As many notches may be provided as is desired, and they are suitably spaced for positioning the movable prongs properly.

To assist in positioning the leaves to be inserted 35 and in shifting them on the prongs, I provide an arched retaining plate 28. The lower edges of the plate are preferably fixed to the base plate 10; and the arched plate walls are spaced from the closed prongs properly to support the edges of the leaves 40 when they are being inserted or shifted on the prongs.

Also to assist in shifting the leaves upwardly towards the bowed portions of the prongs when the binder covers 31 are being closed, I provide 45 automatic boosters 30. When the binder is open, as in Fig. 5, the loose leaves lie down on the binder covers 31, and they must be pushed upwardly onto the bowed portions of the prongs, in order to close the binder covers. This is ac- 50 complished partly by the boosters. These boosters comprise plates 34 which are hinged to the inner edges of the respective strips 11 and 13, or 37 and 39 of Fig. 5. To the outer edge of each plate 34 is hinged a second plate 32, and a 55

roller 33 is journaled on the outer edge of each plate 32. When the covers 31 are folded towards each other, they press against the rollers, and force the shifter plates inwardly and upwardly, as indicated by the dotted lines in Fig. 5, thus pushing the inner edges of the leaves up towards the bowed portions of the prongs. The leaves will then be in position to pass freely along the prongs on each side until they meet at the central portion of the arch.

In order to assist in properly manipulating the boosters, I prefer to form in the covers 31 depressions 35, into which the rollers 33 pass as the binder covers are closing. The rollers are thus held in the positions best adapted for the purpose of suitably operating the boosters. And springs 36 are adapted to press the plates 34 downward when the binder is open and to hold the rollers in the depressions 35 when the binder is closed. Fingers 32a prevent the plates 32 from turning inwardly beyond the depressions.

Fig. 5 illustrates a modification of the means for positioning the prongs properly for closing the binder. These means comprise the strip 40 corresponding to the strip 25 of Fig. 4. Notches 41 are formed in the inner corner of the strip and these are adapted to receive flanges 42 projecting downwardly from the strips 39, or corresponding strips. Fig. 6 illustrates the strip 40 and the notches 41 therein.

Figs. 6 and 7 illustrate modified means for holding the binder in its locked position. These means comprise a plate 45 fixed to the base plate 10, and with a portion thereof spaced from the base plate. A hook 46 is fixed to an operating bar 47. The bar 47 is slidably mounted with reference to the prong-holding bar 48. When the binder is closed, the hook is forced under the plate 45 by the spring 45a holding the binder closed. As the bar 47 is pushed inwardly, the hook is released and the binder may be opened. A spring 44, on the rod 15 with one end passing under the prong plate 39 and the other end over the base plate 10, tends at all times to tilt the prong plate 39 to the open position. A bar 48 is provided for sliding the prongs longitudinally in an ordinary manner.

Fig. 8 illustrates means for forcing the prongs apart. In this case, both sets of prongs are tiltable. When it is desired to open the prongs, the operating bar 50 is forced outwardly, thus operating the arms 51. Each of these arms is pivoted at one end to the base plate 52 by a pivot 53, and to the central portion of the bar 50 by a pivot 54 fixed to the bar 50 playing in a slot 55. The other end of each arm has a cam portion 56. The prong plate 43 of the prongs 57 is rotatably associated with the rod 58, and also rotatably mounted on the rod is a plate 59. As the arm 51 is operated, the cam end passes under the inner edge of the plate 59; and the cam forces the edge of the plate 59 upwardly and rotates the prong support and,

thus, the prongs outwardly, as indicated in Fig. 10. A spring 66, associated with each rod 58, tends at all times to force the prongs to their closed positions.

In Figs. 9 and 10, I illustrate another type of booster. This comprises a thin resilient sheet 60 which is fixed by the edge 61 to the prong strip, and the other edge is positioned to play along the surface of the binder cover 31. As the cover is being closed, the outer edge 62 of the sheet passes into the depression 63 in the cover, and the central portion of the shifter sheet is forced upwardly, to the position indicated by the dotted lines 64. A stiffening strip 65 is fixed to the outer edge of the sheet, to prevent bending of the edge. In these figures are shown also the supports 101 and 109 hereinafter described.

Figs. 9, 10, show a manually operable plate 100 for supporting the leaves to be shifted. This plate preferably extends the full length of the binder, and it is hinged and slidably mounted on supports 101 by means of a rod 102. The supports 101 are fixed with reference to the tiltable prongs 43, one on each end. The plate may be easily tilted upwardly to the operative position by means of a handle 103, and downwardly onto a support 104 to its inoperative position.

In this and similar binders, I provide a leaf-support and guide 109. The fingers 107 of the upper edge of this guide are positioned properly to support the leaves as they are to be passed onto the prongs 108; the entire guide is curved to be parallel with the curve of the prongs, and the guide surface is spaced so as to support the inner edges of the leaves and, thus, prevent sagging or other displacement of the leaves. The fingers 107 pass through the slots 105 when the binder is open and the plate 100 is rotated.

I claim as my invention:

1. In a loose-leaf binder, a frame, two sets of co-operating prongs, one set being mounted for transverse movement on the frame, said frame having a cover board hinged thereto, and means for forcing the loose leaves on one of the sets of prongs upwardly and away from the adjacent cover board, as the board is turned upwardly to its closed position, said means comprising a plate pivoted between the two sets of prongs, and extending between and outside of the prongs to be affected, and a second plate pivoted to the first mentioned plate outside of the latter prongs.

2. In a loose-leaf binder, a base plate, a rod longitudinally mounted on the plate; a prong strip longitudinally mounted on the rod for longitudinal movement thereon; and for rotational movement with reference to its axis, leaf holding prongs fixed to the strip, and a co-operating set of leaf holding prongs mounted on the plate, and means for preventing inward rotating of the rotatable prongs when the sets of prongs are separated and are not properly registering.

ERIK L. KRAG.
